UNITED STATES PATENT OFFICE.

DAVID FRISHMAN, OF NEW YORK, N. Y., ASSIGNOR TO E. & J. BASS INC., OF NEW YORK, N. Y., A CORPORATION.

DESIGN FOR A SALT-SHAKER.

50,907.

Specification for Design. Patented June 12, 1917.

Application filed January 22, 1917. Serial No. 143,883. Term of patent 3½ years.

To all whom it may concern:

Be it known that I, DAVID FRISHMAN, a citizen of the United States, residing at No. 1239 Boston road, New York city, in the borough of the Bronx, county of the Bronx, State of New York, have invented a new, original, and ornamental Design for Salt-Shakers, of which the following is a specification, reference being had to the accompanying drawing, forming part thereof, in which drawing—

Figure 1 is a top view of the salt shaker showing the perforations in the head of the figure through which the salt is shaken.

Fig. 2 is a front view of the salt shaker.

Fig. 3 is a cap fitted into the opening at the bottom of the salt shaker through which opening the salt is filled in the shaker.

I claim—

The ornamental design for a salt shaker as shown.

DAVID FRISHMAN.
